(57)

CLAIM

The ornamental design for a hat, as shown and described.

DESCRIPTION

FIG. 1 is a front left prospective view showing the nature and environmental use of an hat;

FIG. 2 is a right side elevation view thereof;

FIG. 3 is a left side elevation view thereof;

FIG. 4 is a rear elevation view thereof; and,

FIG. 5 is a top plan view thereof.

The broken lines in the drawings represent environmental structure that form no part of the claimed design.

1 Claim, 5 Drawing Sheets
